SULZER FRERES SOCIETE ANONYME, OF WINTERTHUR, SWITZERLAND

HIGH-PRESSURE COMPRESSOR

Application filed January 20, 1928, Serial No. 248,121, and in Switzerland February 24, 1927.

This invention relates to high pressure piston or reciprocating compressors or the like of the kind in which the driving apparatus drives the compressor through the medium of an oscillating column of liquid. The object of the invention is to provide means which will facilitate the removal of the pistons and increase the strength of the piston rod.

According to this invention one or more flexible couplings or clutches are provided between the piston of the compressor and the driving piston, thus not only facilitating the removal of the pistons but also reducing the bending length of the piston rod.

The coupling is preferably mounted in a pivotal and not rigid manner and in a convenient construction one end of the piston rod which is divided into two parts is of spherical shape to engage a correspondingly shaped socket on the other part of the rod. The connection may be such that the two parts of the piston rod can rotate or turn relatively to one another and can also move out of axial alignment. The invention is particularly applicable to the driving pistons of compressors exposed on both sides to the action of a liquid column.

The invention is illustrated by way of example in the accompanying drawing, in which:

Figure 1 shows the application of the invention to a compressor of the type above referred to, and

Figure 2 is a sectional elevation on an enlarged scale, taken on the line 1—1 of Figure 1.

In the compressor shown, the primary piston 5 of the driving machine, connected to the crosshead 3 by the piston rod 4, is actuated by the crank 1 and connecting rod 2. The compressor pistons 6, 7 and 8 are actuated by the liquid column enclosed between the piston 5 of the driving machine and the intermediate pistons, 9, 10 and 11.

According to the present invention a coupling 12 (shown in detail in Figure 2) is provided between the pistons 6 and 9; 7 and 10; and 8 and 11.

From Figure 2 it will be seen that the pis-

ton rod comprises a lower part 13 furnished with a guide 17 and an upper part 14 also provided with guides 15 and 16. The upper part 14 of the piston rod has a spherical end 18 which engages with a correspondingly shaped socket 19 mounted to slide on the face 20 of the lower part 13 of the piston rod.

Engaging a groove 22 in the rod 14 is a two-part ring 21 over which is fitted a ring 23 having its upper surface 24 formed spherical. On this spherical surface bears a spherical socket 25 which can move laterally in the flange 26 which surrounds it.

The lower part 13 of the piston rod is provided in a similar manner with a groove 27 into which is fitted a two-part ring 28. Over the ring 28 is placed a flange 29 which connects together the parts 13 and 14 of the piston rod by being bolted at 30 to the flange 26.

Lubricant is supplied to the coupling 12 through a passage 31 in the lower rod, the chamber 34 between the two overlapping flanges 26 and 29 being thus placed in communication with the chamber 32 containing the oscillating liquid column. The lubricant is forced under the spherical socket 19 whence it passes into the chamber 34.

The invention enables an undivided packing ring to be used in the space 33 as it is only necessary when this packing needs attention to disconnect the coupling 12 and to move the lower part of the piston rod downwards. In spite of the fact that the distance separating the pistons 6, 7 and 8 from the pistons 9, 10, 11 is increased by the use of a coupling, the bending length of the piston rod is reduced.

The upper part 14 of the piston rod can slide in the coupling as the socket is movable and it can also rotate relatively to the lower rod 13 owing to the spherical joint. As a result the piston rod is only exposed to central strains.

I claim:

1. In a high pressure reciprocating compressor, the combination with a primary piston effecting a positive movement, a compressor piston and an oscillating column of

liquid disposed between said pistons to transmit power from said primary piston to said compressor piston, of an intermediate piston arranged between the compressor piston and the liquid column, and a coupling interposed between the compressor piston and the intermediate piston.

2. In a high pressure reciprocating compressor, the combination with a primary piston effecting a positive movement, a compressor piston and an oscillating column of liquid disposed between said pistons to transmit power from said primary piston to said compressor piston, of an intermediate piston arranged between the compressor piston and the liquid column, and a coupling interposed between the compressor piston and the intermediate piston, said coupling comprising a spherical portion of one part of the compressor piston rod and a correspondingly shaped socket on another part of the compressor piston rod, whereby the two parts of the compressor piston rod can be relatively turned and moved out of axial alignment with one another.

In testimony whereof I have affixed my signature.

CHARLES SCHAEER.
